UNITED STATES PATENT OFFICE.

OLINTHUS B. ROBINSON, OF DENTON, TEXAS.

DETERGENT DEVICE.

1,225,496.

Specification of Letters Patent.

Patented May 8, 1917.

Application filed May 7, 1914. Serial No. 837,010.

To all whom it may concern:

Be it known that I, OLINTHUS B. ROBINSON, a citizen of the United States, residing at Denton, in the county of Denton and 5 State of Texas, have invented certain new and useful Improvements in Detergent Devices, of which the following is a specification.

This invention relates to detergent devices, and more particularly to washing machines adapted for the purpose of cleansing 10 articles of apparel.

The primary object of this invention is the provision of a device for the cleansing 15 of clothes or articles of apparel, which consists of a washing machine and a hot and cold water retaining tank, and suitable connections between the washing machine, the cold water supply tank, and the water heating mechanism, whereby the water within 20 the washing machine may be regulated to any desired thermal degree for the proper cleansing of the clothes.

With the foregoing and other objects in 25 view, this invention consists in such novel features of construction, combination, and arrangement of parts as will be hereinafter more fully described, illustrated in the accompanying drawings, and claimed.

30 In describing the invention in detail, reference will be had to the accompanying drawings, wherein like characters of reference designate like or corresponding parts throughout the several views, and in 35 which:—

Figure 1 is a top plan view of the detergent device,

Fig. 2 is a side elevation of the same, showing the water heating device broken 40 away so as to expose the connections between the various tanks and the washing machine, and

Fig. 3 is an end view of the improved detergent device.

45 Referring more particularly to the drawings, 1 designates the washing machine, which is constructed of an outer casing 2, having a rotatable cylinder mounted therein, (not shown), which cylinder is rotated 50 through the medium of a hand wheel 3, which hand wheel is mounted upon a stub shaft 4 journaled in one end of the outer casing. The stub shaft has a gear 5 mounted thereon and is located above the shaft upon 55 which the rotary cylinder (not shown) is carried and upon which is mounted a gear

6 with which it meshes. Said gear 6 is of increased diameter with respect to the gear 5.

The washing machine 1 has connected 60 thereto a pipe 10, which pipe extends from the washer and has direct communication with a tank 11, which tank is formed upon the water heating device not shown. The water heating device consists of any suitable 65 type of furnace mechanism for heating the water. The tank 11 has secured thereto, near its upper end, a pipe 14, which pipe extends laterally from the heat generating mechanism, and has communication with 70 the lower end of a cold water retaining tank 15.

The pipe 14 has communicatively connected thereto a length of pipe 16, which extends transversely of the pipe 14, and is bent 75 at 17, extending downwardly, and has communication with the pipe 10 at 18. A valve 19 is positioned within the pipe 16, near the communication with the pipe 10, which valve controls the flow of water through the 80 pipe 16 and into the pipe 10. A valve mechanism 21 is interposed in the pipe 14, and controls the passage of the water or other liquid from the tank 15 into the tank 11. The pipe 14 has connected thereto, between 85 the valve 21 and the tank 11, a pipe 22, which pipe is bent as at 23 and 24, so as to extend inwardly and downwardly, for communication with the pipe 10. The pipe 22 has a valve mechanism 25 interposed therein, adjacent the connection between the pipe and the pipe 10, for controlling the flow of water through the pipe 22 into the pipe 10.

A valve mechanism 26 is mounted in the pipe 10 and controls the passage of the 90 water from the heat generating device into the washer 1. By the manipulation of the various valve mechanisms as heretofore described, the amount of water permitted to flow into the washer may be regulated as desired, for instance: when it is desired to first wash the clothes, the valve 19 is closed and the valve 21 is opened so as to permit of the flow of cold water from the water retaining tank 15 into the tank 11 of the heating mechanism device, where the water is heated and passes outwardly from the tank 11 through the pipe 10 and into the washer 1. If the water is too hot, the valve 19 may be opened, which will permit of the passage of a certain amount of cold water into the washer, and thus the temperature of the water may 100 105 110

be regulated. If it is desired to admit steam to the interior of the washer, for more thoroughly cleansing the clothes, the valve 21 is closed and the valve 25 opened, which permits of the passage of steam out of the upper end of the tank into the washing machine 1. After the clothes have been thoroughly washed and it is desired to rinse them, the valve 21 is closed and the valve 19 opened, the valve 25 being closed, which will admit the cold water from the retaining tank 15 into the washing machine 1, for thoroughly rinsing the clothes preparatory to wringing them out to dry.

15 In reducing the invention to practice, such minor features of construction, combination and arrangement of parts may necessitate alteration, to which the patentee is entitled, provided such alterations are comprehended within the scope of what is claimed.

20 What is claimed is:—

The combination with a washing machine of an intake pipe connection from the bot-

tom of the shell thereof, a cold water feed tank, a hot water tank, a first pipe leading from said cold water tank to the top of said hot water tank, a valve in said pipe, a second pipe leading from the lower portion of said hot water tank to said intake pipe connection, controlling means for the flow through said second pipe, a third pipe communicating with said first pipe at a point in advance of said valve and leading to said intake pipe connection, means for controlling the flow through said third pipe, a fourth pipe communicating with said first pipe at a point beyond said valve and leading to said intake pipe connection, and a valve in said fourth pipe.

In testimony whereof I affix my signature 40 in presence of two witnesses.

OLINTHUS B. ROBINSON.
